ALTERNATING CURRENT RAILWAY TRACK CIRCUITS EMPLOYING GAS-FILLED ELECTRON TUBES

Paul N. Martin, Penn Township, Allegheny County, Pa., assignor to Westinghouse Air Brake Company, Wilmerding, Pa., a corporation of Pennsylvania

Application April 30, 1946, Serial No. 665,944, which is a division of application Serial No. 545,519, July 18, 1944, now Patent No. 2,541,879, dated February 13, 1951. Divided and this application September 29, 1951, Serial No. 248,953

5 Claims. (Cl. 246—34)

1

My invention relates to alternating current railway track circuits, and more particularly to alternating current track circuits using vacuum tubes for track relays.

The present application is a division of my co-pending application, Serial No. 665,944, filed April 30, 1946, now Patent No. 2,591,456, which is a division of Letters Patent of the United States No. 2,541,879, granted February 13, 1951, for Vacuum Tube Circuits.

When a vacuum tube and particularly a gas tube is used as a relay for a railway track circuit, the bias voltage used to control the conductive condition of the tube must be checked because the loss of a bias voltage might result in the tube being made conductive corresponding to the unoccupied condition of the track circuit when the section is occupied.

Accordingly, a feature of my invention is the provision of track circuit apparatus incorporating novel and improved means to check the bias voltage of a gas tube used as a track relay and to assure proper phase relationship for the voltages of the different tube circuits.

Other features, objects and advantages embodying my invention will appear as the specification progresses.

The foregoing features, objects and advantages embodying my invention are accomplished by a circuit arrangement which includes the shield grid or control electrode and the source of bias voltage in series in a bias circuit, and through which circuit power for the anode circuit is obtained. In this way a loss of the bias voltage or a broken element of the bias circuit results in a loss of power for the anode circuit and the tube cannot be fired in response to such failure. The control grid circuit includes means through which the phase relationship of the voltage applied to the control grid from the track rails can be preselected and thus proper phase relationship between the voltage of the control grid circuit and the voltages of the anode and shield grid circuits can be predetermined.

I shall describe one form of alternating current track circuit apparatus embodying my invention, and shall then point out the novel features thereof in claims.

The accompanying drawing is a diagrammatic

view showing one form of railway track circuit embodying my invention when using a gas tube and an alternating current.

Referring to the drawing, the reference characters 1a and 1b designate the track rails of a stretch of railway track formed by the usual insulated rail joints with a track section D-E, and which section may be one section of a series of sections of a signal system. Section 10 D-E is provided with a track circuit comprising a source of current connected across the rails at one end of the section and a track relay connected across the rails at the opposite end of the section. The immediate source of current 15 for the track circuit of section D-E is a track transformer TE, a primary winding 6 of which is connected to an alternating current transmission line including line wires L1 and L2 connected to a generator, not shown. A secondary winding 7 of transformer TE is connected across the rails 1a and 1b a current limiting impedance 8 being preferably interposed in the connection. 20 The track relay for section D-E comprises a vacuum tube VI and associated circuits. Tube VI may take different forms, and it is disclosed as an indirectly heated gas tetrode having an anode 9, a cathode 10, a control grid 11 and a shield grid 12. Tube VI is provided with two terminals for the shield grid 12, each end of the grid 12 being connected to a terminal. Thus, a 25 circuit connected to the two terminals of the shield grid includes the shield grid in series so that any break in the shield grid or its connections within the tube will interrupt the circuit. The filament of the tube VI is heated from a 30 secondary winding 13 of a line transformer TL, a primary winding 14 of which transformer is connected across the transmission line. 35 Tube VI is provided with a control grid circuit receiving energy from the track rails through a track transformer TRD and a phase shifting impedance. Specifically, a primary winding 40 2 of transformer TRD is connected across the rails 1a and 1b through wires 67 and 68, a resistor 69 being preferably connected in multiple with winding 2. Secondary winding 4 of transformer TRD is included in the control grid circuit which extends from grid 11 through resistor 15 to the junction terminal of an adjustable inductance 16 and a resistor 5 con-

nected in series across the outside terminals of winding 4, and from an intermediate terminal of winding 4 through a bias battery 71 and wire 70 to cathode 10. Thus, the current supplied to the rails through track transformer TE causes a voltage to be applied to the control grid 11 of tube V1, the phase of the voltage applied to the grid with respect to the phase of the voltage across the rails being predetermined through the inductance 16 and resistor 5. The resistor 69 is provided in order to limit the amount of phase shift with changes in ballast conditions, but such resistor may not be needed. Also, the bias battery 71 is provided to give a normal negative bias voltage, but such bias battery may not be required.

Shield grid or control electrode 12 is included in a biasing circuit that can be traced from the right-hand terminal of secondary winding 17 of line transformer TL through wire 18, primary winding 19 of a transformer TP, wire 20, one terminal of the shield grid 12, the shield grid 12, the other terminal of the grid and wire 21 to the left-hand terminal of winding 17. Wire 18 is connected to cathode 10 of the tube through wires 25 and 70, and thus the shield grid 12 is of a potential with respect to cathode 10 proportional to the voltage of secondary winding 17. An anode circuit for tube V1 extends from the top terminal of secondary winding 22 of transformer TP through a battery 72, resistor 23, winding of a relay CR, wire 24, plate 9 and intervening tube space to cathode 10 of tube V1 and wires 70 and 25 to the other terminal of winding 22. It is to be seen that secondary winding 17 of the line transformer TL not only supplies a bias voltage for the shield grid 12 with respect to cathode 10 but also supplies power through transformer TP to the anode circuit of the tube. Thus a loss of power at secondary winding 17 or a broken circuit element for the biasing circuit of shield grid 12 will result in a loss of power for the anode circuit of the tube.

Plus and minus signs have been placed on certain of the circuit elements of the drawing to indicate the relative polarity of the parts during one half cycle of the voltage of the transmission line L1—L2, the relative polarity of these circuit parts being reversed from that indicated during the other half cycle of the voltage. During the half cycle, the voltage is that indicated by the plus and minus signs, the shield grid 12 is negative in potential with respect to cathode 10 and the anode 9 is positive in potential with respect to the cathode. The parts are so proportioned that the higher voltages of such half cycle applied to the anode are sufficient to fire the tube, except for the negative bias effected through the shield grid 12. It is to be pointed out that battery 72 is of a voltage insufficient to fire tube V1 and serves to aid in preselecting the portion of the cycle of the alternating voltage supplied through transformer TP and the tube is conductive. The battery 72 may not be needed and may be omitted.

Normally, that is, when the track section D—E is unoccupied, the control grid 11 is driven positive in potential with respect to cathode 10 during the half cycle the anode 9 is positive and such positive voltage for the control grid 11 causes tube V1 to be fired and relay CR energized by the anode current. During the following half cycle of the voltage the anode 9 is negative with respect to the cathode 10 and the tube is deionized. On the next positive half cycle the tube is fired again so that relay CR is energized by impulses of

the anode current and its armature is retained picked up as long as such impulses of current flow because of the slow release characteristic of the relay. It is to be observed that the proper phase relationship of the voltage applied to the control grid 11 is preselected by the adjustment of the inductance 16 and resistor 5.

When the track section D—E is occupied, the control voltage impressed across control grid 11 and cathode 10 is shunted and the tube V1 remains non-conductive because of the bias voltage applied to the shield grid 12.

It is apparent that there is disclosed in the drawing a track circuit using a gas tube as a track relay and through which tube a control relay CR is retained energized in response to the track section being unoccupied and is deenergized when the section is occupied. Furthermore, a loss of power at winding 17 of the line transformer so that there is a loss of bias voltage for the shield grid 12 results in a loss of power for the anode circuit and the tube cannot be fired because of such failure. Also, any broken circuit element for the shield grid circuit results in a loss of power for the anode circuit and the tube cannot be fired because of such a broken circuit element.

It is to be understood that my invention is not limited to a shield grid as the control electrode 39 of a tube, to be provided with two terminals and included in series with a bias voltage source, and other tube electrodes can be used.

Although I have herein shown and described but one form of alternating current railway track circuits embodying my invention, it is understood that various changes and modifications may be made therein within the scope of the appended claims without departing from the spirit and scope of my invention.

Having thus described my invention, what I claim is:

1. In a railway track circuit, the combination comprising, a track section, a source of alternating current connected across the rails at the exit end of the section; a gas tube having an anode, a cathode, a control grid and a shield grid; a line transformer having a primary winding connected to said current source; another transformer, a shield grid circuit including in series a secondary winding of said line transformer, a primary winding of said other transformer and said shield grid; said cathode connected to said shield grid circuit at a point intermediate said secondary winding of the line transformer and said primary winding of said other transformer to bias said shield grid with respect to the cathode, an anode circuit connected between said anode and cathode and including a secondary winding of said other transformer, said secondary winding poled for said shield grid to be negative in potential with respect to said cathode the half cycle of said alternating current source said anode is positive in potential with respect to said cathode to avoid firing said tube, means to connect said track rails across said control grid and cathode, said last mentioned means being poled for said track circuit current to drive said control grid positive in potential with respect to the cathode to fire the tube each half cycle said anode is positive, and control means connected to said anode circuit energized when said tube is conductive.

2. In a railway track circuit the combination comprising, a track section, a source of alternating current, means including a track transformer to connect said source across the rails adjacent

one end of the section, a gas tube having an anode, a cathode and a first and a second control grid; said second control grid provided with two terminals one connected to each end of the grid to include the grid in series between the two terminals, a line transformer provided with a primary and a secondary winding and having its primary winding connected to said current source, another transformer provided with a primary and a secondary winding; a biasing circuit including in series said secondary winding of said line transformer, said primary winding of said another transformer and said second control grid with its two terminals; an anode circuit including said secondary winding of said another transformer, said anode and tube space to said cathode and a connection to said biasing circuit at a point intermediate the secondary winding of the line transformer and the primary winding of said another transformer, said biasing and anode circuits poled for said second grid to be negative in potential with respect to the cathode the half cycle of the alternating current said anode is positive in potential with respect to the cathode, circuit means including a phase shifting means to connect said first control grid and cathode across the rail adjacent the other end of said section, said circuit means poled for the voltage derived from said track transformer through the track section to render said first control grid positive in potential with respect to the cathode the half cycle of the alternating current said second control grid is negative in potential with respect to the cathode whereby the anode circuit is effective to fire the tube, and control means connected to said anode circuit energized by the current thus caused to flow in the anode circuit when the tube is fired.

3. In a railway track circuit the combination comprising, a track section, a source of alternating current, means to connect said source across the rails at one end of said section; an electron tube having an anode, a cathode and a first and a second control grid; said second control grid provided with two terminals one connected to each end of the grid to include the grid in series between the two terminals, a line transformer provided with a primary and a secondary winding and having its primary winding connected to said source, another transformer provided with a primary and a secondary winding; a biasing circuit including in series said secondary winding of said line transformer, said primary winding of said another transformer and said second control grid with its two terminals; an anode circuit including said secondary winding of said another transformer, a control relay and said anode and tube space to said cathode, a point of said anode circuit intermediate the cathode and said secondary winding of said another transformer being connected to said biasing circuit at a point intermediate said secondary winding of the line transformer and said primary winding of the another transformer, said anode and biasing circuit poled for said second control grid to be negative in potential with respect to said cathode the half cycle of the alternating current said anode is positive in potential with respect to the cathode whereby said anode circuit is ineffective to render said tube conductive, circuit means including a phase shifting means to connect said first control grid and cathode across the rails at the other end of said section and poled for the voltage derived from said track rails due to the energy supply through the track transformer to render said first

grid positive in potential with respect to the cathode the half cycle the second grid is negative in potential with respect to the cathode, whereby said anode circuit is effective to render the tube conductive and energize said relay by the current thus caused to flow in the anode circuit.

4. In a railway track circuit the combination comprising, a track section, a source of alternating current, means to couple said source across the rails at one end of said section to apply a voltage to the rails; a gas tube having an anode, a cathode and a first and a second control grid; said second grid provided with two terminals one connected to each end of the grid; energy transfer means including a first, second and a third winding, said first and said second windings being electrically connected, said first winding inductively coupled to said current source to receive a voltage, said second and said third windings being inductively coupled, a biasing circuit including in series said first and second windings and said second grid and its two terminals, said biasing circuit being energized by the voltage induced in said first winding, said cathode connected to said biasing circuit intermediate said first and second windings whereby the second grid has a given bias voltage with respect to said cathode due to the voltage drop in said second winding, an anode circuit including said third winding and connected across said anode and cathode, said third winding coupled to said second winding to inductively receive a voltage due to the biasing circuit current flowing in said second winding, said voltage induced in said third winding having a magnitude effective to fire the tube but maintained ineffective to fire the tube due to said given bias voltage of the second grid with respect to said cathode, circuit means having a phase shifting means to connect said first control grid and cathode across the rails of said section to apply the voltage of the rails to the first grid, said circuit means being poled for the voltage thus applied to the first grid to counteract said bias voltage of said second grid and enable the voltage of said third winding to fire the tube, and a relay having a winding interposed in said anode circuit and energized by the current flowing in said anode circuit due to the firing of said tube.

5. In a railway track circuit, the combination comprising, a track section, a source of alternating current, means including a track transformer to connect said source across the rails at one end of said section; an electron tube having an anode, a cathode and a first and a second control grid; said second grid provided with two terminals one connected to each end of the grid, a line transformer provided with a primary and a secondary winding and having its primary winding connected to said current source; an auxiliary transformer having a first and a second winding; a biasing circuit including said secondary winding of the line transformer, said first winding of said auxiliary transformer, a first one of said terminals, said second grid and a second one of said terminals; said cathode connected to said biasing circuit at a selected terminal of said secondary winding of the line transformer whereby said second grid is biased with respect to the cathode due to the voltage of said secondary winding, an anode circuit connected across said anode and cathode and including said secondary winding of said auxiliary transformer and a control relay, the voltage induced in said secondary winding of said auxiliary transformer effective to cause conductive current to flow through said

7
tube but maintained ineffective due to said bias voltage of said second grid, circuit means to connect said first grid and cathode across the rails of said section to apply to the first grid a voltage derived from said source through the rails of the 5 section, said circuit means poled for said voltage applied to said first grid to counteract said bias voltage of said second grid and render the voltage of said secondary winding of said auxiliary trans-

former effective to cause current to flow through said tube and energize said relay.
